Patented Apr. 27, 1976

239,694

FILE OR RASP ALSO CAPABLE FOR USE AS A PLANE

Brian Ward, Retford, and David Scarrow, Dinnington,
near Sheffield, England, assignors to Aven Tools
Limited, Maltby, Rotherham, England

Filed Mar. 14, 1974, Ser. No. 451,267

Claims priority, application Great Britain Sept. 17, 1973

Term of patent 14 years

Int. Cl. D8—03, 05

U.S. Cl. D8—90

FIG. 1 is a perspective view from above and one side of a file or rasp capable for use as a plane.

FIG. 2 is an underneath plan view of the file or rasp capable for use as a plane when adapted for use as a plane.

FIG. 3 is a view of the file or rasp taken in the direction of arrow 3 in FIG. 1.

FIG. 4 is a view of the file or rasp taken in the direction of arrow 4 in FIG. 1.

FIG. 5 is an underneath plan view of the file or rasp capable for use as a plane showing the handle in an alternative position and the blade when reversed, the pattern of the blade being consistent over the whole area of the blade.

We claim:

The ornamental design for a file or rasp capable for use as a plane, as shown and described.
